[57] CLAIM

The ornamental design for an identification holder for a luggage case or the like, as shown and described.

DESCRIPTION

FIG. 1 is a perspective view of an identification holder for a luggage case or the like showing our new design.

FIG. 2 is a front elevational view.

FIG. 3 is an end elevational view.

FIG. 4 is a top plan view.

FIG. 5 is a rear elevation view.

FIG. 6 is a bottom plan view.

FIG. 7 is a perspective similar to FIG. 1 with the holder lid open; and

FIG. 8 is an end elevational view similar to FIG. 3 with the holder lid open.
